UNITED STATES PATENT OFFICE.

OTTO HEINIGKE, OF NEW Utrecht, NEW YORK, ASSIGNOR TO THE HARTFORD CARPET COMPANY, OF HARTFORD, CONNECTICUT.

DESIGN FOR A CARPET.

SPECIFICATION forming part of Design No. 18,375, dated October 31, 1882.

Application filed August 11, 1882. Term of patent 3½ years.

To all whom it may concern:

Be it known that I, OTTO HEINIGKE, of New Utrecht, in the State of New York, have invented a new and original Design for Carpets, of which the following is a specification.

5 This invention relates to a new and original design for carpets and similar fabrics; and it consists in the novel grouping and configuration of figures hereinafter more fully described.

10 The accompanying photograph illustrates a face view of a carpet having my new design.

The background is filled in with short irregularly-curved tendril-like figures arranged in small sets. Over this ground are scattered at 15 irregular intervals closely-massed bunches of small star-shaped flowers, each in a setting of small leaves, and connected with each other by small curving branches that bear, irregularly scattered along their length, similar small leaves, in clusters of twos and threes, and at 20 irregular intervals over the design clusters of flag-like leaves occur, as shown in the accompanying photograph.

I claim—

1. The design for carpets, consisting of the 25 ground filled in with tendril-like forms, substantially as shown.

2. The design for carpets, consisting of the 30 flower clusters and connecting leafy stems, substantially as shown.

3. The design for carpets, consisting of the 35 flower clusters and connecting leafy stems and the groups of flag-like leaves, substantially as shown.

4. The design for carpets, consisting of the 35 flower clusters and connecting leafy stems, the groups of flag-like leaves, and the ground filled in with tendril-like forms, substantially as shown and described.

OTTO HEINIGKE.
